R. H. CARPMAEL

CLOSURE FOR CONTAINERS

Filed Sept. 3, 1927

INVENTOR:

RICHARD HERBERT CARPMAEL,
By his Attorneys,

Richard H. Carpmael

Patented June 5, 1928.

1,672,055

UNITED STATES PATENT OFFICE.

RICHARD HERBERT CARPMAEL, OF MOULTON, ENGLAND.

CLOSURE FOR CONTAINERS.

Application filed September 3, 1927, Serial No. 217,429, and in Great Britain July 14, 1926.

This invention relates to improvements in or modifications of the invention described in my United States Patent No. 1,651,669 and application Serial No. 168,709 in which I have described a closure comprising essentially a resilient or spring disk having a central bulged portion capable of being sprung into release and secure position, the first of which is above and the second below the horizontal.

According to one feature of this invention the peripheral fingers of the disk are formed with an outward flare at their ends, and the internal wall of the mouth of the container is provided with a corresponding tapering recess.

Preferably that portion of the internal wall of the mouth of the container above the tapering recess is flared outwardly, and such that the diameter of the mouth is slightly larger than the spread of the peripheral fingers when in the release position.

According to a further feature of the invention, a sealing member may be provided attached to the underside of the disk and in addition to, or instead of, the outer cap. Preferably, in this case an additional ledge is provided on the inner wall of the mouth of the container, and against which the sealing member bears. If desired, the sealing member may be detachably connected to the underneath of the disk.

The invention is illustrated in the accompanying drawings in which Figure 1 is a sectional view of the modification in which the peripheral fingers are flared outwardly at their ends.

Fig. 1^A is a modified form of the disk in Fig. 1.

Figures 2 and 3 are sectional views of other modifications.

In the drawings *a* designates the disk generally, *b* the peripheral fingers, *c* the neck of the container having a recess *j* and ledge *i* for receiving the flanges *k* of the fingers. *g* is the outer cap.

Referring now to Figure 1, a form of disk is shown having a double action and in which the flanged ends of the peripheral fingers, which are preferably provided in the former construction illustrated, are dispensed with. The disk *a* has peripheral fingers *b* which flare outwardly at their lower ends and engage when in the secure position, with a tapering recess *j'* in the

mouth of the container formed above the ledge *i*. The mouth of the container from the top of the recess *j'* having an outward flare as shown at *j''*, preferably such that the diameter of the mouth is slightly larger than the spread of the peripheral fingers when in the release position (corresponding to the view shown in Figure 2 of application Serial No. 168,709).

This double action consists in that, in addition to the "click" made by the bulged portion or diaphragm of the disk, when being moved past the mid-position, there will be felt the spring in the peripheral fingers as they give when being moved past the shoulder formed by the recess *j'* and flare *j''*. Thus in a closure of the type shown in Figure 4 of said Patent 1,651,669 having a disk as shown in Figure 1 to move from the secure or closed, to the release or open position, it is first of all necessary to actuate the shaft *f* to move the bulged portion *d* to the open position, and then pull on the closure, when the peripheral fingers will move past the shoulder referred to above and move inwardly slightly in doing so, without affecting the diaphragm. Extraction or removal of the closure is thus mechanically as well as frictionally resisted.

The reverse action takes place to close.

A further advantage lies in the fact that should it be tried to apply the closure to a container, when the bulged portion of the disk is in the secure position (i. e. the peripheral fingers having their maximum spread, such as would normally cause them to engage the wall of the mouth of the container) owing to the flare *j''* of the mouth, this will be found possible without in any way damaging it, whereas in the form of disk, the peripheral fingers of which are flanged at their ends, it would have been impracticable without damaging the fingers and disk, and curtailing the life of the spring.

It is evident, if it is desired to obtain a closure which may be removed in one operation or pull it is only necessary to so proportion the doming of the diaphragm that the outward flare of the fingers in the open or release position is smaller than the tapering recess in the mouth of the container. Then the closure is retained in position by the action of the diaphragm of the disk only.

It is obvious also that the disk shown in

Figure 1 may be modified so as to be operated in the same manner as the disks shown in the other figures of the drawings, as for instance the operating knob and sealing disk shown in Figure 3 may be applied to the disk shown in Figure 1.

Figure 1^A shows a modified construction of the form of disk shown in Figure 1.

Referring now to Figure 2, the operating shaft *f* is provided with a pin or projection *f'* co-operating with the surface *o* on the cap *g* which surface is cammed as shown, so that on rotating the knob *e* which in this case is preferably milled, the pin *f'* rides upon the cam surface causing the displacement of the central bulged portion *d* of the disk.

In Figure 3 the mouth of the container is provided with an additional ledge *i''* which may be formed to house a washer, and a sealing member *g'* which may replace the outer cap *g*, is provided attached to the disk *a*. It should, however, be understood that the sealing member *g'* may be separate from the disk *a*, and also an outer cap provided.

Moreover in practice, it will be found that when a closure has been positioned and a ledge is employed, as soon as the disk has moved to the secure position the flanges on the ends of the peripheral fingers draw away from the ledge so that there will be a slight clearance between the lower surface of the flange and the ledge.

If desired, the closure may be hinged or pivotally connected to the container or like member to which it is to be applied, and the hinge may be connected either to the outer cap or disk according to the form of closure employed.

It should be understood that although the present type of disk is only illustrated in the form in which it is fast with the outer cap, it may be employed alone as illustrated in Figures 1, 2 and 3 of my said Patent 1,651,669 or in conjunction with an outer cap and operating shaft as shown in Figure 4 thereof. Further the disk may be treated so as to act as a spring disk as shown in Figures 1 and 2 of my second application No. 168,709, or be modified in a manner similar to the other modifications shown therein.

What I claim is:—

1. A closure for containers comprising the combination with a resilient disk formed with a number of peripheral fingers having an outward flare and capable of being sprung into release and secure positions, of a container the internal wall of whose mouth is provided with a tapering recess with which the fingers engage when in the secure position.

2. A closure for containers comprising the combination with a resilient disk formed with a number of peripheral fingers having

an outward flare and capable of being sprung into release and secure positions, of a container the internal wall of whose mouth is provided with a tapering recess with which the fingers engage when in the secure position, an outer cap connected to the disk and adapted when the closure is applied to rest upon the top of the mouth of the container. 70

3. A closure for containers comprising the combination with a spring disk formed with a number of peripheral fingers having an outward flare and capable of movement into release and secure positions but which are biased under their own action normally to assume one of said extreme positions, of a container the internal wall of whose mouth is provided with a tapering recess with which the fingers engage when in the secure position. 75

4. A closure for containers comprising the combination with a resilient disk formed with a number of peripheral fingers having an outward flare and capable of being sprung into release and secure positions, of a container the internal wall of whose mouth is provided with a tapering recess forming a ledge, said fingers in the secure position engaging said recess. 80

5. A closure for containers comprising the combination with a resilient disk formed with a number of peripheral fingers having an outward flare at their ends and capable of being sprung into release and secure positions, of a container the internal wall of whose mouth is provided with a tapering recess with which the fingers engage when in the secure position to mechanically as well as frictionally resist removal of the closure. 95

6. The combination with a closure as claimed in claim 5 of an outer cap connected to the disk and adapted when the closure is applied to rest upon the top of the mouth of the container. 100

7. The combination with a closure as claimed in claim 5 of a shank fast with the disk and an outer cap mounted on said shank on which it has limited movement corresponding to the displacement of the disk. 110

8. A closure for containers comprising the combination with a resilient disk formed with a number of peripheral fingers having an outward flare at their ends and capable of being sprung into release and secure positions, of a container the internal wall of whose mouth is provided with a tapering recess with which the fingers engage when in the secure position, and which above the recess is flared outwardly such that the diameter at the mouth is slightly larger than the spread of the peripheral fingers of the disk when in the release position. 120

9. The combination with a closure as claimed in claim 5 of an outer cap connected to the disk and adapted when the closure is applied to rest upon the top of the mouth. 130

of the container which above the recess is flared outwardly such that the diameter is slightly larger than the spread of the peripheral fingers of the disk when in the release position.

10. A closure for containers comprising the combination with a spring disk formed with a number of peripheral fingers having an outward flare at their ends and capable of movement into release and secure positions but which are biased under their own action normally to assume one of said extreme positions, of a container the internal wall of whose mouth is provided with a tapering recess with which the fingers engage when in the secure position.

11. A closure for containers comprising the combination with a spring disk formed with a number of peripheral fingers having an outward flare at their ends and capable of movement into release and secure positions but which are biased under their own action normally to assume one of said extreme positions, of a container the internal wall of whose mouth is provided with a tapering recess with which the fingers engage when in the secure position, and means on the disk for operating the closure.

12. A closure for containers comprising the combination with a spring disk formed with a number of peripheral fingers having an outward flare at their ends and capable of movement into release and secure positions but which are biased under their own action normally to assume one of said extreme positions, of a container the internal wall of whose mouth is formed with a tapering recess with which the fingers engage when in the secure position, and an outer cap connected to the disk and adapted when the closure is applied to rest upon the top of the mouth of the container.

13. A closure for containers comprising the combination with a spring disk formed with a number of peripheral fingers having an outward flare at their ends and capable of movement into release and secure positions but which are biased under their own action normally to assume one of said extreme positions, of a container the internal wall of whose mouth is formed with a tapering recess with which the fingers engage when in the secure position to mechanically as well as frictionally resist removal of the closure, a shank fast on the disk and an outer cap mounted on said shank on which it has limited movement corresponding to the displacement of the disk.

14. A closure for containers comprising the combination with a spring disk formed with a number of peripheral fingers having an outward flare at their ends and capable of movement into release and secure posi-

tions but which are biased under their own action normally to assume one of said extreme positions, of a container the internal wall of whose mouth is provided with a tapering recess with which the fingers engage when in the secure position, and means on the disk for operating the closure, a shank fast on the disk, an outer cap mounted on said shank on which it has limited movement corresponding to the displacement of the disk and means for locking the disk in the secure and/or release positions to prevent displacement of the central portion with respect to the outer cap.

15. A closure for containers comprising the combination with a spring disk formed with a number of peripheral fingers having an outward flare at their ends and capable of movement into release and secure positions but which are biased normally under their own action to assume one of said extreme positions, of a container the internal wall of whose mouth is provided with a tapering recess with which the fingers engage when in the secure position, and which above the recess is flared outwardly such that the diameter at the mouth is slightly larger than the spread of the peripheral fingers of the disk when in the release position.

16. A closure for containers comprising the combination with a spring disk formed with a number of peripheral fingers having an outward flare at their ends and capable of movement into release and secure positions but which are biased normally under their own action to assume one of said extreme positions, of a container the internal wall of whose mouth is provided with a tapering recess with which the fingers engage when in the secure position, and which above the recess is flared outwardly such that the diameter at the mouth is slightly larger than the spread of the peripheral fingers of the disk when in the release position, and an outer cap connected to the disk and adapted when the closure is applied to rest upon the top of the mouth of the container.

17. A closure for containers comprising the combination with a spring disk formed with a number of peripheral fingers having an outward flare at their ends and capable of movement into release and secure positions but which are biased under their own action normally to assume the secure position, of a container the internal wall of whose mouth is provided with a tapering recess with which the fingers engage when in the secure position.

In testimony that I claim the foregoing as my invention I have signed my name this 25th day of August, 1927.

RICHARD HERBERT CARPMAEL.
